UNITED STATES PATENT OFFICE.

WILLIAM RICHEY McMURRAY, OF BELFAST, IRELAND.

OPENWORK-STITCHING MACHINE.

1,184,256.

Specification of Letters Patent. Patented May 23, 1916.

Application filed November 12, 1913. Serial No. 800,489.

To all whom it may concern:

Be it known that I, WILLIAM RICHEY McMURRAY, a subject of the King of Great Britain, residing at Belfast, Ireland, have 5 invented certain new and useful Improvements in Openwork-Stitching Machines, of which the following is a specification.

This invention relates to the production of open work stitching such as the well 10 known "shire", "spoke", or like stitching. At present it is usual to either draw the threads by hand and then effect the sewing operation or to employ a sewing machine having a punch or spreader, this punch or 15 spreader moving in a vertical path either along with or independently of the needle or needles.

Under my invention I provide on or attach to the sewing machine for doing open- 20 work stitching and which may be of the usual well known "Wheeler & Wilson", "Singer", or other suitable construction, spreader blades so arranged and operated that they perform a combined vertical move- 25 ment and also a lateral movement, the blades entering the fabric and pushing the threads thereof apart in such manner as to obviate the necessity for pulling or drawing a number of threads or for using punches or spears 30 as at present. The blades are arranged in advance of the needles and positively push aside the threads.

In order that the invention may be properly understood I have hereunto appended 35 explanatory sheets of drawings, whereon I have shown, by way of example, different ways of carrying out the invention.

On the drawings: Figures 1, 2 and 3, show one arrangement, in front elevation at Figs. 40 1 and 2, and in side elevation at Fig. 3. In Fig. 1 the spreader blades are shown closed and in Fig. 2 they are shown open. Figs. 4 and 5 show another arrangement in front and side elevation. Fig. 5^a shows a battery 45 of spreader blades and Fig. 5^b shows how the blades enter the cloth. Fig. 6 shows a third arrangement in front elevation and Fig. 7 a sectional detail of part of this arrangement. Figs. 8 and 9 show a fourth arrangement in 50 front and side elevation respectively.

Referring to the drawings whereon the same reference letters, wherever repeated, indicate the same or similar parts: A is the

head of the machine, B is the needle bar, C the presser foot, and D the presser bar. 55

In the arrangement shown at Figs. 1 to 3, the machine has a pair, or one or more pairs, of spreaders or spreader blades *a*, *b*, arranged to operate in the manner of a pair of scissors, these spreaders being pivotally 60 secured at *c* to the block *d* of the needle bar and in advance of the ordinary vibrating needles *e*, *f*. In this arrangement each spreader, or, if desired, battery of spreaders, is provided with an extension *a*¹, *b*¹, and 65 these extensions may be flat or of rectangular section for the whole or part of their length and are connected together, at their upper ends, by means of a spiral spring *g* in such manner that they are normally held 70 in the closed position, as at Fig. 1, under the action of the said spring. The extensions *a*¹, *b*¹, are provided with cam pieces *a*², *b*², adapted to engage and work on a wedge block *h* on the head *A* of the sewing ma- 75 chine. The block *h* is adjustable vertically and for this purpose is provided with slots *h*¹ and screws *i*. When the block has been adjusted the screws, which pass into the head, are tightened up so that the block is 80 held rigidly in position. The pivot pin *c* is made one with the plate *c*¹ which latter may be detachably secured to the block *d*. With this arrangement, when the vibrating needles of the sewing machine are out of the 85 cloth and in their up position, the spreader blades *a*, *b*, are also raised up out of the cloth and assume the position shown in Fig. 1, but, on the downstroke of the needle bar B, after the spreader blades have entered 90 the cloth, the cam pieces *a*², *b*², engage the wedge block *h* and force the blades apart in the manner shown at Fig. 2 so that the blades positively push aside the threads in the cloth. The block *h* is, or may be, made, 95 as shown, so as to retain the spreader blades in the open position not only while in the cloth on the downstroke but also during part of the upstroke of the needle bar.

In the arrangement shown at Figs. 4 and 5 100 the extensions *a*¹, *b*¹, are normally held close together by means of a spiral spring *g* as before and they are pushed apart by the action of a wedge *m* at the lower end of a bar *m*¹, secured to a pivot pin *m*² working in a 105 bearing on the head which latter is slotted

for a short distance to allow movement of the bar m^1 . Secured also to the pin m^2 is a bar n whose lower end is straight but whose upper end is angled, as shown at Fig. 5. 5 On the needle bar B is a roller o which is adapted to engage the bar n . A spiral spring p normally pulls the wedge m backward. With this arrangement, at each descent of the needle bar B , the roller o acts on the incline of the bar n and, consequently, forces outward the wedge m and, as this wedge projects between the two extensions a^1, b^1 , it forces them apart, and, consequently, opens the spreaders in the same manner as in the 15 arrangement Figs. 1, 2 and 3. So long as the roller maintains contact with the straight part of the bar n the spreaders are maintained in the open position. The wedge m may be of a conic shape as shown.

20 In the arrangement shown at Fig. 6, the extensions a^1, b^1 , are normally held closed by the action of the spring g and are opened at the proper times by means of a cam q carried on a spindle q^1 (see Fig. 7) suitably 25 mounted in the head of the machine. On this spindle, at the inner end thereof, is a spur pinion q^2 which is capable of being engaged by a rack q^3 carried on the needle bar B . With this arrangement, at each descent of the needle bar, the cam q which is of elliptical shape, is turned sufficiently to push apart the extensions a^1, b^1 , and open out the spreader blades.

30 In the arrangement shown at Figs. 8 and 35 9, the extensions a^1, b^1 , are forced apart by a conic wedge m as before, and are closed by a spring g as before but, in this case, the wedge m is suitably moved outward at the proper times. The spreader blades are, as 40 shown, preferably, made slightly longer than the usual vibrating needles so as to enter the cloth before the same. It may be found desirable to provide more than one blade or spreader on each movable arm a^1, b^1 , for 45 example as shown at Fig. 5^a where each arm carries three spreader blades and they would, preferably, be so pitched relatively to the feed of the fabric that the two sets of spreader blades will enter consecutively into 50 alternate spaces between the threads at each spreading operation after each forward feed of the fabric (see Fig. 5^b which shows the spreader blades in full lines as at the end of one stitching operation and in dotted lines 55 as at the end of the next stitching operation).

Having now fully described my invention, what I claim and desire to secure by Letters Patent is:—

60 1. The combination, with a sewing machine having a needle bar, a needle or needles attached to said needle bar, and means for operating same, of automatically acting and laterally moving means arranged on 65 said needle bar and in advance of said nee-

dle or needles, for positively opening out the threads of the fabric before the same is sewn.

2. The combination, with a sewing machine having a vibrating needle or needles 70 and means for operating same, of automatically acting and laterally moving blades arranged in advance of said needle or needles, for positively opening out the threads of the fabric before the same is sewn. 75

3. The combination, with a sewing machine having a needle bar, a needle or needles attached to said needle bar, and means for operating same, of automatically acting and laterally moving blades pivotally 80 mounted on said needle bar and arranged in advance of said needle or needles, for positively opening out the threads of the fabric before the same is sewn.

4. The combination, with a sewing machine having a vibrating needle or needles and means for operating same, of automatically acting and laterally and vertically moving blades arranged in advance of said needle or needles and adapted to positively 90 open out the threads of the fabric before the same is sewn. 85

5. The combination, with a sewing machine having a needle bar, a needle or needles attached to said needle bar, and means for operating same, of automatically acting and laterally moving thread spreading blades mounted on said needle bar and moving therewith in advance of said needle or 95 needles. 100

6. The combination, with a sewing machine having a needle bar, a needle or needles attached to said needle bar, and means for operating same, of a block on said needle bar, automatically acting and laterally 105 moving thread spreading blades mounted on said block and moving therewith in advance of said needle or needles.

7. The combination, with a sewing machine having a vibrating needle or needles 110 and means for operating same, of spreader blades movably arranged in advance of said needle or needles, means for moving the blades laterally apart and means for bringing the spreader blades together. 115

8. The combination, with a sewing machine having a vibrating needle or needles and means for operating same, of a pair of spreader blades arranged in line and in advance of said needle or needles and means 120 for vibrating the spreader blades laterally.

9. The combination, with a sewing machine having a needle bar, a needle or needles attached to said needle bar and means for operating same, of a pair of spreader 125 blades arranged on said needle bar and in advance of said needle or needles and means for vibrating the spreader blades laterally.

10. The combination, with a sewing machine having a vibrating needle or needles 130

and means for operating same, of a pair of spreader blades arranged in line and in advance of said needle or needles and means for moving the spreader blades apart from 5 one another at intervals.

11. The combination, with a sewing machine having a needle bar, a needle or needles attached to said needle bar, and means for operating same, of a pair of spreader blades movably carried on said needle bar in advance of said needle or needles, extensions on the spreader blades, means acting on the extensions for forcing the blades laterally apart and means for bringing the 15 blades together again.

12. The combination, with a sewing machine having a needle bar, a needle or needles attached to said needle bar, and means for operating same, of a pair of spreader blades movably carried on said needle bar in advance of said needle or needles, extensions on the spreader blades, means acting on the extensions for forcing the blades laterally apart and means acting on the extensions 25 for bringing the blades together again.

13. The combination, with a sewing machine having a needle bar, a needle or needles attached to said needle bar, and means for operating same, of a pair of spreader blades pivotally carried on said needle bar in advance of said needle or needles, extensions on the spreader blades, means acting on the extensions for forcing the blades laterally apart and means for bringing the 35 blades together again.

14. The combination, with a sewing machine having a needle bar, a needle or needles attached to said bar and means for operating same, of a pair of spreader blades 40 pivotally carried on the needle bar in advance of said needle or needles, extensions on the spreader blades, a wedge acting on the extensions for forcing the blades laterally apart and a spring for bringing the 45 blades together again.

15. The combination, with a sewing machine having a needle bar, a needle or needles attached to said bar and means for operating same, of a pair of spreader blades pivotally carried on the needle bar in advance 50 of said needle or needles, extensions on the spreader blades, an adjustable wedge acting on the extensions for forcing the blades laterally apart and a spring for bringing the 55 blades together again.

16. The combination, with a sewing machine having a needle bar, a needle or needles attached to said bar and means for operating same, of a pair of spreader blades 60 movably carried on the needle bar in advance of said needle or needles, extensions

on the spreader blades, means acting on the extensions for forcing the blades laterally apart and elastic means for bringing the blades together again. 65

17. The combination, with a sewing machine having a needle bar, a needle or needles attached to said needle bar, and means for operating same, of a pair of spreader blades movably carried on said needle bar 70 one in advance of the other and both in advance of said needle or needles, extensions on the spreader blades, means acting on the extensions for forcing the blades laterally apart and means for bringing the blades together again. 75

18. The combination, with a sewing machine having a needle bar, a needle or needles attached to said needle bar, and means for operating same, of a pair of spreader 80 blades movably carried on said needle bar one in advance of the other and both in advance of said needle or needles, extensions on the spreader blades, means acting on the extensions for forcing the blades laterally 85 out of line and means for bringing the blades again into line.

19. The combination, with a sewing machine having a needle bar, a needle or needles attached to said needle bar, and means for operating same, of a pair of spreader 90 blades movably carried on the said needle bar in advance of said needle or needles, extensions on the spreader blades, means acting on the extensions for forcing the blades 95 at intervals laterally apart and means for bringing the blades together again.

20. The combination, with a sewing machine having a needle bar, a needle or needles attached to said needle bar, and means for operating same, of a pair of spreader 100 blades removably fitted on said needle bar in advance of said needle or needles, extensions on the spreader blades, means acting on the extensions for forcing the blades laterally apart and means for bringing the 105 blades together again.

21. The combination with a sewing machine having a needle bar, a vibrating needle or needles attached to said needle bar 110 and means for operating same, of means for opening out the threads of the fabric arranged on the needle bar in advance of the needle or needles and adapted to be moved vertically therewith and laterally independently of the vibrating movement thereof. 115

In testimony whereof I affix my signature in presence of two witnesses.
